UNITED STATES PATENT OFFICE.

METRO J. KINDRAT AND HAWRYIL ZATZERKOWNY, OF DETROIT, MICHIGAN.

COIN-CONTROLLED MEANS.

Original application filed March 7, 1925, Serial No. 13,735. Divided and this application filed December 18, 1926. Serial No. 155,722.

This invention relates to certain new and useful improvements in newspaper dispensing machines and has for its primary object to provide a machine that is automatic in its operation, the mechanism for delivering the newspaper through a slotted opening in a side wall of the machine casing being placed in operation upon the depositing of a coin in the machine.

Another object of the invention is to provide an improved coin-controlled mechanism for rendering the newspaper delivery means operative.

This application relating to coin controlled mechanism for dispensing machines, is a division of applicant's co-pending application filed March 7, 1925, Serial Number 13,735, which has merged into Letters Patent No. 1,622,262, dated March 22, 1927.

With the above general objects in view and others that will appear as the nature of the invention is better understood, the same consists in the novel form, combination and arrangement of parts hereinafter more fully described, shown in the accompanying drawing and claimed.

In the drawing wherein like reference characters designate corresponding parts throughout the several views,

Figure 1 is a vertical longitudinal sectional view showing the coin operated mechanism and the delivery device for the newspaper with a stack of newspapers supported within the machine casing;

Figure 2 is a horizontal sectional view taken on line 2—2 of Figure 1 showing the spring motor operated mechanism and the newspaper delivery arms;

Figure 3 is an enlarged fragmentary side elevational view of a part of the coin controlled mechanism; and

Figure 4 is a fragmentary perspective view showing the coin box and the rod for opening the hinged bottom thereof.

The newspaper dispensing machine disclosed in this application embodies a casing having front and rear walls 1 and 2, side walls 3 and 4 and top and bottom walls 5 and 6, the casing being preferably mounted upon supporting feet 7 while entrance thereto is gained through a hinged side door 8.

To support a stack of newspapers P within the casing as shown in Fig. 1, a spring supported platform and elevating means

therefor are provided and embody a pair of tensioned rollers 9 parallel with the front and rear walls 1 and 2 adjacent the upper end of the casing while a pair of cooperating guide shafts 10 are similarly journaled adjacent the lower end of the casing. The rollers 9 and shafts 10 are provided with sprocket wheels 11 at each end thereof and over which endless sprocket chains 12 travel. The paper supporting platform 13 is secured at its corners as at 14 to the inner sides of the sprocket chains 12 and upon movement of the sprocket chains, the platform 13 is raised and lowered.

The cushion support for the platform 13 embodies a tapering helical spring 15 having the upper convolution thereof secured to a plate 16 that is centrally anchored to the lower face of the platform 13 while the lower larger convolution of the helical spring is secured to the stand 17 spaced upwardly of the bottom wall 6 of the casing as shown in Fig. 1. In order to hold the platform in its lowered position for the purpose of placing a stack of papers P thereon, there is provided a shaft 18 journaled adjacent the stand 17 with a hand operated crank handle 19 upon one end thereof, the drum 20 fixed to said shaft intermediate the ends thereof having a cable 21 wound thereon with the free spent end secured at 22 to the plate 16 and platform 13.

Upon rotating the shaft 18 in the proper direction, the cable 21 is wound thereon and the platform 13 is lowered for compressing the spring 15 as illustrated and the platform is retained in its lowered position by the hook 23 carried by the stand 17 placed into engagement with the eye 24 carried by the plate 16. With the platform so lowered, the door 8 of the casing being opened, a stack of papers is mounted upon the platform to the desired elevation.

The prime movers for the platform comprise the rollers 9 that are rotatively tensioned in one direction.

The platform 13 travels upwardly in a step by step movement during the dispensing of newspapers through the opening 32 in the front wall of the casing as shown in Fig. 1 and when the last paper has been dispensed, the sign plate 33 carried by the inner sides of the sprocket chains 12 adjacent the front wall 1 of the casing and hav-

ing the legend "Empty" thereon will be positioned in alinement with the window 35 in the front wall 1 of the casing to indicate that all of the newspapers have been sold. 5 When all of the newspapers have been delivered, a lever 50, diagrammatically shown in Fig. 1, applies brake devices for rendering the tensioned rollers 9 inoperative.

The mechanism for delivering the newspapers from the stack 8 to the exit opening 32 in the front wall 1 of the casing includes a spring motor having a shaft 53 provided with a key end 54, the key end of the shaft being journaled in the elongated bearing 56 10 that extends to the opposite wall 4 of the casing as shown in Fig. 3. A coil spring 57 surrounds the shaft 53, the spring being of the band type with the inner end thereof anchored to the shaft while the outer end of 15 the spring is anchored to the cylindrical casing 58. It will therefore be seen that upon rotating the shaft 53 through the medium of the key end 54 the band spring 57 is placed under tension and is so retained by the 20 spring pressed pawl 59 engaging the ratchet wheel 60, shown more clearly by dotted lines in Fig. 1, it being noted that the ratchet wheel 60 is fixed to the shaft 53. A gear wheel 61 fixed to an end of the spring casing 25 58 meshes with the pinion 62 upon the shaft 63 located beneath the motor shaft 53 and the shaft 63 has a gear 64 thereon that meshes with the pinions 65 and 66, respectively mounted upon the crank shafts 67 and 30 68 journaled in the side walls 3 and 4 of the casing. It will therefore be seen that when the spring motor is in operation, the crank shafts 67 and 68 are rotated.

Crank portions 69 and 70 are carried by 40 the crank shafts 67 and 68 respectively, each crank shaft being preferably provided with four crank portions and with which newspaper delivery arms 71 are associated as shown in Figs. 1 and 2, each of the arms 71 45 having an offset shoulder portion 72 and upwardly arched from the shouldered portion to the forward end thereof as at 73 with a slotted portion 74 in the arched portion of each arm with which the crank portions 50 70 of the shaft 68 are associated, a roller bearing 75 on each crank portion reducing friction between the parts as shown in Fig. 1. The arms 71 are supported by the crank portions of the shafts 67 and 68 and the forward end of each arm carries a finger 76 55 hinged to the arm as at 77 and spring pressed as at 78 for normally influencing the pin 79 carried by the finger into piercing engagement with the upper newspaper in the stack 60 P as shown in Fig. 1. When the spring motor is in operation, the crank shaft 67 operates to move the arms 71 in a forward direction toward the paper exit opening 32 while the crank shaft 68 associated with the 65 slotted arched portions of said arms elevates

the forward ends of the arms during rotation thereof for disengaging the fingers 76 from the upper paper in the stack.

Devices are provided for holding the spring motor against operation and coin operated mechanism is associated with said devices, the crank shaft 68 having a pinion 80 fixed thereto intermediate its ends that meshes with the worm 88^a upon the shaft 88 that is journaled in frame 89. The pinion 81 fixed to the shaft 82 as shown in Figs. 2 and 3 meshes with worm 88^a, this mechanism being similar to the disk rotating mechanism of a phonograph. A disk wheel 83 fixed to the shaft 82 has a cam formation on its peripheral edge with a stop shoulder 84 that is engaged by the finger 85 for holding the disk wheel 83 against rotation and also acting as a stop for the driving devices and spring motor associated with the paper delivering arms 71. To control the speed of operation of the spring motor and its associated mechanism, a horizontal gear 86 fixed to the upper end of the shaft 88 meshes with a pinion 87, the supporting shaft of 90 which carries a speed governor 90. This driving mechanism reduces the strain on the finger 85 and assures a relatively slow and even movement of the parts.

The finger 85 forms a part of the coin operated mechanism and is carried by a rack segment 91 journaled in the casing which meshes with the rack segment 92 formed at one side of the larger rack segment 93 journaled in alinement with the segment 91 while the rack segment 93 meshes with the rack segment 94 that carries the arm 95. The rack segment 94 is pivotally supported as at 96 and has a coin cup 97 fixed to the outer end thereof while a link 98 connects the arm 95 to the coin gage bar 99 that is pivotally supported as at 100 with a block 101 slidable thereon for determining the denomination or weight of the coin for tilting the coin box 97. A bottom 102 is hinged to the coin box at 103 and is normally retained in its closed position by the spring 104 positioned between the bottom 102 and the arm 95. The bottom 102 of the coin box is opened by the lever 105 pivoted within the casing as at 106, one end of the lever 105 having a link connection 107 with the crank 108 carried by the shaft end 82^a while the other end of the lever 105 carries a depending rod 109 that engages the side arm extension 102^b carried by the coin box bottom 102 and open the same against the tension of the springs 104 in a manner to be presently described. A coin chute 110 extends through the front wall 1 of the casing at its upper end and a coin inserted therein will fall into the cup 97 for operating the coin released mechanism, while an improper coin will pass through the chute and be returned through the return chute 111.

In the use of the newspaper dispensing machine disclosed in this application, and assuming that the platform 13 for supporting the stack of papers P is at its limit of upward movement, the door 8 is opened and by rotating the shaft 18 through the medium of the crank handle 19, the cable or cord 21 attached at its upper end to the platform is wound upon the drum 20 with the platform lowered against the tension of the spring 15 for compressing the latter. During the lowering movement of the platform, the rollers 9 are revolved by the chain and sprocket mechanism connected to the platform and placed under tension.

When a coin of the proper denomination is inserted into the coin chute, the same will be delivered into the coin cup 97 and the weight of the coin in the cup will cause a lowering movement thereof and relative movement of the meshing rack segments 91 to 94 to disengage the finger 85 from the stop shoulder 84 upon the periphery of the disk wheel 83, it being understood that during this movement the bottom 102 of the coin box remains in its closed position. With the finger 85 disengaged from the stop shoulder 84 upon the disk wheel 83, the spring motor associated with the shaft 53 operates the chain of gearing, crank shafts 67 and 68 and shaft 82 that has the crank connection 108 with the lever 105, operation of the lever 105 causing the rod 109 to be moved in a downward direction to open the bottom 102 of the coin box to permit the discharge of coin into a suitable receptacle. The speed of operation of the mechanism is controlled by the governor 90 and worm 88 interposed between the pinions 80 and 81.

When the crank shafts 67 and 68 are rotated, the paper delivering arms 71 are moved forwardly and the pin 79 upon the finger 76 engaging the upper paper of the pile as shown in Fig. 2 projects the forward edge of the paper through the delivery opening 32 in the front wall of the casing. Rotation of the crank shaft 67 causes the crank portion 69 thereof to move the arm 71 in a forward direction while the crank shaft 68 having the crank portion 70 associated with the slot 74 in the upwardly arched portion 73 of said arm causes an elevation at the forward end of the arm to disengage the finger 78 from the paper.

When the finger 85 is disengaged from the shoulder 84, rotation of the disk wheel 83 is permitted, and when the coin has been discharged from the cup 97, the finger 88 is restored to engagement with the periphery of the disk wheel and in position to engage the wheel shoulder 84 upon completion of one revolution and again arrest the delivery mechanism.

While there is herein shown and described the preferred embodiment of the present invention, it is nevertheless to be understood that minor changes may be made therein without departing from the spirit and scope of the invention as claimed.

What we claim as new is:—

1. In coin operated mechanism for newspaper dispensing machines, the combination with dispensing means and means for operating the dispensing means, of coin released devices for rendering the operating means effective and comprising a coin cup, a series of meshing rack segments, a lever connection between one end segment and the coin cup, a disk wheel having a cam-edge and an abutment shoulder operated by the operating means and a finger carried by the other end segment engaging the cam shoulder to hold the operating means inoperative.

2. In coin operating mechanism for newspaper dispensing machines, the combination with dispensing means and means for operating the dispensing means, of coin released devices for rendering the operating means effective and comprising a coin cup, a series of meshing rack segments, a lever connection between one end segment and the coin cup, a disk wheel having a cam-edge and an abutment shoulder operated by the operating means, a finger carried by the other end segment engaging the cam shoulder to hold the operating means inoperative, and a speed governor associated with the disk wheel.

3. In coin operated mechanism of the type described, the combination with a rotatable shaft, of a disk wheel fixed to the shaft and carrying a peripheral abutment, coin releasable means associated with the abutment for controlling rotation of the shaft, and including a chain of rack segments, an arm carried by each end segment with one arm cooperating with the abutment and a coin cup carried by the other arm.

4. In coin operated mechanism of the type described, the combination with a rotatable shaft, of a disk wheel fixed to the shaft and carrying a peripheral abutment, coin releasable means associated with the abutment for controlling rotation of the shaft, and including a chain of rack segments, an arm carried by each end segment with one arm cooperating with the abutment and a coin cup carried by the other arm, a spring closed hinge bottom for the coin cup and means rendered operable upon rotation of the shaft for opening the cup bottom for discharge of the coin.

In testimony whereof we affix our signatures.

METRO J. KINDRAT.
HAWRYIL ZATZERKOWNY.
